UNITED STATES PATENT OFFICE.

ELMER C. LONG, OF HANNIBAL, MISSOURI, ASSIGNOR TO LONG SILENT MOTOR COMPANY, OF HANNIBAL, MISSOURI, A CORPORATION OF MISSOURI.

INTERNAL-COMBUSTION MOTOR.

1,165,522.

Specification of Letters Patent. Patented Dec. 28, 1915.

Application filed December 16, 1911. Serial No. 666,117.

To all whom it may concern:

Be it known that I, ELMER C. LONG, a citizen of the United States of America, residing at Hannibal, in the county of Marion 5 and State of Missouri, have invented certain new and useful Improvements in Internal-Combustion Motors, of which the following is a specification.

This invention relates more especially to 10 valve mechanisms for internal combustion motors, and to the adaptation of the principles of my invention to certain constructional features adapting the motor to be simply and durably constructed and to be 15 efficient in operation.

One of the objects of the present invention is to provide an improved construction, combination and arrangement of parts in a 20 slow movement valve mechanism of the type shown, described, and claimed in my co-pending application, S1. No. 656,975 October 26, 1911.

More specifically, an object is to provide 25 an improved air cooling valve movement.

Another object is to provide an improved 30 crank driven valve mechanism by means of which the admission is caused to open later and close earlier than in the above mentioned application, and whereby the exhaust is caused to remain open for a comparatively long period of travel of the main piston.

A further object is to provide a construction which makes it possible to employ a 35 valve movement of shorter travel with a corresponding curtailment in the dimensions of the valve operating links.

An ancillary object toward the attainment 40 of this end is to provide an improved adjustable connection between the valve proper and the driving gear therefor.

With these and other objects in view, which will appear in the specification and be specifically pointed out in the appended 45 claims, my invention contemplates the principles of operation and the construction and arrangement of parts exemplified in the accompanying drawings showing an adaptation of my invention, and in which,

Figure 1 is a vertical section of an internal combustion motor, constructed in accordance with the principles of the present invention. Fig. 2 is a section on the line 50 II-II, Fig. 1. Fig. 3 is a section on the line III-III, Fig. 1. Fig. 4 is a section on

the line IV-IV, Fig. 1. Fig. 5 is an enlarged detail section on the line V-V, Fig. 3. Fig. 6 is a diagrammatic view, showing the relative positions of the several parts when the exhaust valve is about to open. Fig. 7 is a similar view, showing the relative positions of the parts when the exhaust valve has just closed and the admission valve is beginning to open.

Referring more particularly to the drawings, and for the sake of convenience, confining my description more especially to the embodiment shown therein, the main engine crank shaft 1, which may be common to any desired number of engine units, may be suitably journaled in the lower crank case housing 2, and, for each unit of the engine, is provided with a crank 3 whose crank pin 4 is journaled in the end of a pitman 5 whose upper end is journaled upon a pin 6 carried by the piston 7, said piston being reciprocably mounted in the cylinder 8 which is in open communication through passageways 9 and 10 with valve chambers 11 and 12, respectively.

The inlet valve chamber 11 is provided with an admission port 13 and the exhaust valve chamber 12 is provided with an exhaust port 14. Valves of peculiar construction, to be presently described, are reciprocably mounted in these valve chambers, said chambers being provided with removable caps 15 and 16 which make the valves freely accessible from above.

For the sake of providing a valve movement which will be perfectly balanced at all times, and an improved construction for cooling said valves by air, I construct them in the manner illustrated best in Fig. 1, in which the hollow cylindrical ends 17 and 18 are connected by a contracted neck portion 19, the inner wall of the neck portion 19 being provided with a plurality of heat radiating rings 20 which provide a central air channel 21, said rings being each provided with a plurality of apertures 22 arranged in circular series to provide air passages through the respective rings. In this manner, free radiation from the piston valve is provided in the interior thereof where the heat is taken up by air which is pumped through the piston valve during its reciprocation, suitable air intakes 33 being provided for the valve crank case housings.

In order to provide a crank driven ad-

mission valve which opens relatively late and closes relatively early, and a crank driven exhaust valve which is open during a relatively long period of travel of the main piston and closes quickly, I preferably mount on opposite sides of the main crank shaft 1, and at some distance thereabove, a pair of valve crank shafts 23 and 24 which are offset to one side of the axis of movement of said valves and rotate in the same direction as the main crank shaft. Within each motor unit, a crank pin 25 driven by the shaft 23 serves to drive a valve pitman 26 for the inlet valve, and a similar crank pin 27 serves to drive a pitman 28 for the exhaust valve. This arrangement of the valve crank shafts necessitates the provision of adjustable connections interposed between the respective valves and their crank shafts in order to regulate the times at which the inlet and exhaust valves open and close. For this purpose, I preferably employ the device shown in Figs. 3, 4 and 5, in which is shown a cross head annulus 29 with its periphery threaded to the inner wall of the lower cylindrical portion 18 of the valve, so that said annulus may be adjusted at will to bring about an exact correlative relationship between the valves and the port openings, such relation being determined under actual running conditions.

In order to provide simple and efficient means for maintaining the annulus 29 in any position to which it may be adjusted, lock bolts 30 are threaded lengthwise through off-set walls of said annulus, and are adapted to engage at their inner ends against a suitable shoulder formed around the inner piston wall to jam the annulus or cross head. The lock bolts 30 are, in turn, locked in position by jam nuts 31.

By an inspection of Fig. 1, it will be noted that the valve crank case housings are separate and distinct from the main crank shaft housing, each of said housings being made to conform closely to the path of travel of the rod ends therethrough, thus providing an efficient splash system for lubricating the several parts.

Referring now to Fig. 2 of the drawings, I preferably arrange the cylinders in groups of two within an outer jacket or housing 32 which provides the usual water cooling chamber, which in conjunction with the improved arrangement of the valve crank shafts above the path of travel of the main crank shaft, enables me to bring the valve housings in close juxtaposition to their respective cylinders, thereby reducing to a minimum the course of the gases through

said cylinders and housings, and moreover, enabling me to gain a maximum efficiency in the consumption of the explosive mixture.

By an inspection of Fig. 1, together with the diagrammatic views shown in Figs. 6 and 7, it will be seen that when the exhaust opens, the main crank pin is approximately at the middle of its slow movement corresponding to the dead center position of the piston. In consequence, the main piston becomes accelerated on its upward travel during the initial portion of the exhaust period so that the scavenging of the cylinder is for the most part accomplished while the valve is wide open. Furthermore, by the time the exhaust valve is approximately closed, the piston has reached its upper dead center slow movement, and a small initial downward movement of the piston prior to the opening of the admission valve creates a partial vacuum and produces a sharp rapid admission.

What I claim is:

1. A tubular valve open at both ends and provided with cylinder bearing portions adjacent its ends, a contracted neck portion connecting said cylinder bearing portions, said neck portion having a series of circularly formed radiating projections on its inner wall extending the entire length thereof, said radiating portions being provided with apertures.

2. A tubular valve open at both ends and provided with cylinder bearing portions adjacent its ends, a contracted neck portion connecting said cylinder bearing portions having a series of horizontally arranged radiating flanges mounted on the inner wall thereof, and an adjusting annulus carrying a wrist pin mounted on one of said cylindrical bearing ends.

3. In an internal combustion motor, a closed valve housing, a hollow valve reciprocatable therein and open at both ends, cylinder bearing portions formed on said valve adjacent the ends thereof, circularly formed heat radiating projections located adjacent the central portion of the inner wall of said valve, said portions being provided with apertures for the passage of air, and an adjusting annulus carrying a wrist pin turnably mounted on one of said cylindrical bearings, said projections adapted to agitate the atmosphere contained in said housing.

ELMER C. LONG.
